UNITED STATES PATENT OFFICE.

JOHN R. LEE, OF EXCELSIOR SPRINGS, MISSOURI.

METAL TRIM.

Application filed February 20, 1922. Serial No. 537,754.

To all whom it may concern:

Be it known that I, JOHN R. LEE, a citizen of the United States, residing at Excelsior Springs, in the county of Clay and State of Missouri, have invented certain new and useful Improvements in Metal Trims, of which the following is a specification.

My invention relates generally to metal trims for door and window casings, base caps, etc., and the present invention may be regarded as an improvement on U. S. Letters Patent No. 1,170,968, which I duly acquired by assignment.

One feature of the invention resides in providing the metal trim with hooks or projections to which wire lath can be readily attached without the use of nails or other extraneous fastening devices.

Another feature resides in a metal sheath for holding the margin 3 of the metal trim in place on studding, window and door frames, etc., so that said margin will not have to be secured with nails, the heads of which remain exposed and lend an unfinished appearance to the job, as shown by Figs. 1 and 3 of the above-mentioned patent.

In the accompanying drawings, Fig. 1 is a fragmentary perspective view showing the metal trim attached to a door jamb and a stud.

Fig. 2 is a fragmentary sectional view of the metal trim applied to the inner and outer sides of a window frame.

Fig. 3 is a vertical sectional view showing the metal trim applied as a sanitary wainscoting cap.

Fig. 4 is a fragmentary perspective view of a portion of the metal trim designed chiefly for the ornamental finish of a door or window opening, together with a sheath to receive the exposed margin of the metal trim.

Fig. 5 is a fragmentary perspective view of a portion of the metal trim designed more particularly for the subbase or dado of a wall.

Corresponding parts throughout the several views are indicated by the same reference characters.

The metal trim disclosed by Fig. 4 consists of a body portion 1, a base 2, and a marginal portion 3, which latter projects outwardly from the body portion 1 of the trim and is folded to form a double thick-

ness, which heretofore has been secured in place in a building by nails, the heads of which remained exposed and gave the job an unfinished appearance. In order to overcome the latter objection I provide one of the important features of the present invention, such feature consisting of a metal sheath 6 of, substantially, J-shape in cross section and comprising front and rear flanges 8 and 10, respectively, united by a curved portion 12.

The front and rear flanges 8 and 10, respectively, are spaced apart to receive the margin 3 of the metal trim, the flange 8 overlapping the front portion of said margin while the rear flange 10 underlies said margin as shown more clearly in Figs. 1 and 2. The flange 10 is wider than the flange 8, so that nails such as, A, can be driven through the former without disturbing the latter when securing the sheath 6 to studding or the frame of a door or window.

Referring again to the base 2 of the metal trim, said base 2 has hooks 14 struck up therefrom at intervals to provide fastening means for wire lath such as B, when the same is employed instead of the wooden lath indicated at C.

In practice the sheath 6 is first secured in position by driving nails through the rear flange 10. The margin 3 of the metal trim is then slipped into the sheath 6 between the flanges 8 and 10, whereby said margin 3 is firmly held. The rear portion of the base 2 is then secured by nails as indicated at D. By thus securing the metal trim by means of the sheath 6 and the nails D, said metal trim is firmly held in place and all nails employed are hidden from view when the job is finished.

The metal trim disclosed by Fig. 5, is substantially the same as that disclosed by Fig. 4, as indicated by corresponding reference numerals with exponents *a*, hence further description thereof is deemed unnecessary.

While I have shown the sheath 6 and the hooks 14 associated with metal trims corresponding with those disclosed in the patent above referred to, it is to be understood that the hooks 14 may be formed on other shapes of metal trim, while the sheath 6 can be employed to secure the exposed margin of such other trim in place. Said hooks 14

may, also, be made square, round, pointed, or of any other configuration, and the base 2 of the metal trim, instead of being nailed to the studding or other support, may be 5 provided with slots 20 for the passage of screws which may be substituted for the nails in holding the trim in place.

Having thus described my invention, what I claim and desire to secure by Letters Patent, is:

- 10 1. In a metal trim, a base portion thereto, and projections struck up from said base portion and to which metal lath may be attached, substantially as described.
- 15 2. In combination with a metal trim having an exposed marginal portion, a sheath adapted to receive said marginal portion and provided with flanges extending the length of the marginal portion to overlap

and underlie the same, for the purpose set 20 forth.

3. In combination with a metal trim having an exposed marginal portion of double thickness, projections struck up from the base of said trim to support metal lath, a 25 substantially J-shaped sheath to receive and hold said marginal portion and provided with flanges extending the length of the marginal portion to overlap and underlie the same, the underlying flange being wider 30 than the overlapping flange, for the purpose described.

In testimony whereof I affix my signature, in the presence of two witnesses.

JOHN R. LEE.
